UNITED STATES PATENT OFFICE.

LUCRETIA LESTER, OF CUBA, NEW YORK.

FIRE-ESCAPE.

SPECIFICATION forming part of Letters Patent No. 485,954, dated November 8, 1892.

Application filed June 18, 1892, Serial No. 437,111. (No model.)

To all whom it may concern:

Be it known that I, LUCRETIA LESTER, a citizen of the United States of America, residing at Cuba, in the county of Allegany and State 5 of New York, have invented certain new and useful Improvements in Fire-Escapes; and I do hereby declare the following to be a full, clear, and exact description of the invention, such as will enable others skilled in the art 10 to which it appertains to make and use the same, reference being had to the accompanying drawings, and to letters of reference marked thereon, which form a part of this specification.

15 This invention relates to that class of fire-escapes in which a rope is employed in connection with a friction device, whereby a person may lower himself to the ground from a building or structure; and it consists in the 20 construction and combination of the parts, as will be hereinafter fully set forth, and particularly pointed out in the claims.

In the accompanying drawings, forming a part of this specification, Figure 1 is a view 25 showing the application of my invention. Fig. 2 is a perspective view. Fig. 3 is a longitudinal section. Fig. 4 is a sectional view on the line *x* *x* of Fig. 3.

The friction-clutch of the fire-escape is 30 made up of two parts A and B, which are pivotally connected to each other at their upper ends and at their lower ends are provided with hooks *a* and *b*, which extend in the same direction, one hook being adapted to engage

35 with a belt placed around the waist of the person using the device, while the other prevents the hand slipping off the clamping portion of the section B, and for this reason the hook *b* has a smaller curve than the hook *a*.

40 The sections A and B are corrugated longitudinally, and these corrugated surfaces are grooved or channelled to receive the rope, so that when the sections are clamped upon said rope it will be given a number of small bends to 45 retard its progress through the device. The section A is provided above its hook with an outwardly-projecting lug *a'*, having an aperture *d*, through which the rope passes to prevent it swinging away from the section, the 50 rope being also confined between the upper

ends of the two sections. The upper end of the section A is provided with outwardly-projecting portions *ee*, which fit over the reduced upper end of the section B and are connected thereto by a pivot-bolt. By reducing the upper end of the section B shoulders *ff* are provided, against which the projecting portions *ee* of the section A will strike and prevent the sections swinging far apart. It will 55 also be noted that the section B has a portion which extends above the pivot toward the aperture through which the rope passes, so that should the operator lose control of the device by letting go of the same frictional contact of the rope with the end of the section B above the pivot will cause the lower end of said section to swing outwardly and clamp or jam upon the rope, so as to bring the friction device to a dead-stop, thus giving the person who is using the clamp an opportunity to properly manipulate the same by grasping and drawing the sections toward each other, which movement regulates the frictional contact of the sections upon the rope, so that the descent can be regulated. 70

The device, besides being used as shown in the drawings and as described, may also be used by a person in a building to lower another person or object, in which case the device is reversed upon the rope and the hook *a* passed 80 over a stationary object, so that the rope can be paid out between the sections.

Having thus described my invention, what I claim as new, and desire to secure by Letters Patent, is—

1. In a frictional fire-escape, the combination of the jaws A and B, having a series of corrugations with central recesses, said sections being pivoted to each other, substantially as shown, and for the purpose set forth. 90

2. In a frictional fire-escape, the combination of the sections A and B, provided with corrugations having central recesses, and a pivot for securing the parts to each other, one of the sections having a straight portion above 95 and to one side of the pivot, substantially as shown, and for the purpose set forth.

3. In a frictional fire-escape, the combination of the sections A and B, having corrugated inner faces, one of the sections having 100

a projecting lug, with an aperture serving as a guide for the rope, and a hook *a*, outwardly-extended portion having a pivot to one side or out of line with the aperture *d*, a section 5 B, having a straight portion above the pivot, shoulders *ff*, and a hook at the end farthest from the pivot, substantially as shown.

In testimony whereof I affix my signature in presence of two witnesses.

LUCRETIA LESTER.
